UNITED STATES PATENT OFFICE.

CLARENCE CARSON, OF NEW ROCHELLE, NEW YORK, ASSIGNOR TO H. W. JOHNS-
MANVILLE COMPANY, A CORPORATION OF NEW YORK.

SPEEDOMETER.

1,319,204.

Specification of Letters Patent.

Patented Oct. 21, 1919.

Application filed June 10, 1915, Serial No. 33,254. Renewed August 6, 1919. Serial No. 315,788.

To all whom it may concern:

Be it known that I, CLARENCE CARSON, a citizen of the United States, and resident of New Rochelle, in the county of West-
chester and State of New York, have invented certain new and useful Improvements in Speedometers, of which the following is a specification.

My invention relates in general to speedometers of a type particularly designed for use in connection with motor vehicles or other machines subjected to vibration or jerking movements and the invention particularly relates to improvements in unitary inserts constituting the mechanical part of such instruments.

It has been usual in this art to supply speedometers in numerous sizes and to construct the different mechanical elements thereof proportionate to the different sizes of instruments, each size or type being designed and constructed complete in itself.

It is one of the objects of my invention to construct the mechanical parts together with a carrying frame of one standard size forming a unit which can be carried in stock. With these units there is also carried in stock inclosing casings of different standard sizes and reading dials of different standard sizes provided with scales of different ranges, each designed to co-act with the standard mechanical units. With this interchangeability of unit parts carried in stock, it is possible, when an order is received for a certain character of instrument, to take one of these mechanical units and adjust the same for installation in the required size casing or to fit the required size dial or scale and in this way any size or type of instrument can be supplied from stock provided the required size casing or type of dial is available.

This I am enabled to attain with the device hereinafter described, simply by shifting a minor part of the mechanical structure and properly mounting the same in the desired type or size of casing.

Speedometers of the centrifugally actuated type are usually inaccurate especially at low speeds and accordingly it is a further object of the invention to provide a construction for attaining an accurate speed reading irrespective of the speed of the driving parts and to provide such an instrument which will at the same time be capable

of indicating an accurate reading over a relatively long range of speeds.

It is among the other objects of the invention to provide a structure designed so as to permit of a delicate calibrating of the same; so that the dial indicator shall be free from any tremulous or jerky movement; so that the moving parts shall be free from backlash or other loose connections and so that there will be a minimum of friction or wear.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

Referring to the accompanying drawings:

Figure 1 is a front view of a preferred embodiment of my invention with the dial removed and certain parts broken away to show internal construction;

Fig. 2 is a longitudinal sectional view taken on the line 2—2 of Fig. 1 looking in the direction indicated by the arrow;

Fig. 3 is a portion of the governor of Fig. 2 shown in action;

Fig. 4 is a plan view looking down on the device and with portions of the casing and supporting frame in section;

Fig. 5 is a view similar to Fig. 1 showing the mechanical unit mounted in a casing larger than the casing shown in Fig. 1;

Fig. 6 is a front elevation of the complete device shown in either Figs. 1 or 5;

Fig. 7 is a horizontal sectional view taken on the line 7—7 of Fig. 6 looking in the direction indicated by the arrows; and

Fig. 8 is a view in elevation of the rear side of the adjustable dial actuating cam.

In the following description and in the claims, parts will be identified by specific names for convenience of expression but they are intended to be as generic in their application to similar parts as the art will permit.

In the drawings there is shown a mechanical unit including a supporting frame 10 of any convenient configuration, best suited for installation in the different styles of casings and shown to be a circular band 110

provided with laterally extending and oppositely disposed supports 11 and 12 cast integral therewith and constituting a spacing means for localizing the units in a containing casing. The ends of each of the supports 11 and 12 are provided with tapped holes adapted to receive respectively the pairs of screws 13 and 14, the former of which are designed to pass through the rear 5 wall of the containing casing hereinafter described to fasten the units thereto and the latter of which are designed to fasten the mounting plate 15 demountably in position at the front of the completed instrument 10 and spaced from the frame 10. The frame 10 is provided at a point therein intermediate the supports with a hub 16 having an annular opening 17 diametrically disposed relative to the circular frame in which opening 15 is positioned an end thrust bearing member 18 for a driving shaft 20. This bearing member also constitutes a ball bearing cap providing a runway in which is contained anti-friction devices 19, such as ball-bearings, positioned between the runway and the cone shaped end of the shaft 20. Hubs 21 and 22 are provided on the frame 10 diametrically positioned opposite the bearing 25 18, the latter of which hubs project externally of the outlines of the frame 10 and is provided with a reduced threaded portion 23 by means of which the device may be mounted in position or by means of which a container of the driving element may be attached. The hubs 21 and 22 form in effect a continuous cylinder, the bore 24 of which is internally threaded and in which is adjustably mounted a bearing block 25, through which extends the shaft 20. The 30 outer end of the shaft extends beyond the hub 22 and is designed to be operatively connected to any member the speed of which is to be ascertained. This bearing block 25 constitutes an end thrust bearing for limiting 35 the movement of the shaft away from the end thrust bearing 18 and for this purpose is provided with a runway in which is positioned anti-friction devices 26 such as roller bearings, which are moved by the adjustment 40 of the bearing block 25 into bearing engagement with the shoulder 26' formed on the shaft 20. In order to adjust and lock the bearing block in place, the other end thereof is provided with screw-driver slots 27. 45 The block is locked in position by a lock-nut 28 also provided with screw-driver slots 29; slots 27 and 29 being designed so as to be simultaneously engaged by a compound screw-driver insertible through the bore of 50 the hub 22. The driving shaft 20 constitutes a governor shaft and is provided with a centrifugally actuated governor consisting of weights 30 arranged in a circle. These 55 weights may be of any shape and number and in the form illustrated are shown to be

three in number and to be substantially sections of a circle in plane and co-act to form a sectional ring shaped centrifugally controlled member. Each of the weights is provided with a pair of links 31 and 32 with 70 their adjacent ends pivotally connected to the weight intermediate its depth by means of a pin 33. One, or more, of the links is provided adjacent the pivotal connection provided by the pin 33 with a stop 34 adapted to engage the other link and thus limit the outward throw of the weight 30. The links 31 are pivotally secured by means of pins 35 to a collar 36 fixed to the governor shaft 20 adjacent the end thrust bearing member 18. The links 32 are pivotally secured by means of pins 37 to a collar 38 fixed to the runner 39 which is slidably mounted on the governor shaft 20 and which constitutes the speed controlled member of the device. A 80 relatively heavy tension spring 40 and a relatively light tension spring 41 are disposed in order between the stationary collar 36 and the runner 39 with their adjacent ends bearing on opposite sides of a collar 42 slidably mounted on the shaft 20. The runner 39 is in the form of a sleeve having a relatively long bearing on the shaft and provided with a pair of laterally projecting disks 43 extending perpendicular to the axis 95 of movement of the same and spaced apart longitudinally of said axis to form an annular runway therebetween. The bore of said sleeve is enlarged intermediate its ends which bear on the shaft to provide an annular pocket 44 and the sleeve is provided with air vents 45 for permitting the escape of air from said pocket during the sliding movement of the runner. 100

The indicator actuating mechanism is 105 carried on the mounting plate 15 and is removable therewith from the frame 10 as a unit. This mechanism comprises a pair of shafts journaled in the mounting plate 15 and in the bridge plate 54 affixed to the rear 110 face of the mounting plate. One of the shafts 51 projects rearwardly through the bridge plate, which projected portion has a crank arm 48 adjustably fastened thereto by means of a collar 52 fastened to the shaft 115 by a set-screw 53. The crank includes an arm or stud 46 provided with a rounded head 47 adapted to be inserted in the runaway 74 so that the movement of the runner will rock said crank and its shaft. The 120 shaft 51 is enlarged between the plates 14 and 54 to prevent longitudinal movement thereof and the portion thereof adjacent the plate 15 has a sector gear 55 adjustably fastened thereto and designed to mesh continually with a small pinion 56 secured to the other shaft 57. A spring 61 has one end secured to a post 60 extending rearwardly from the mounting plate 15 and has its opposite end attached to the 125 130

notched extension 49 depending from the crank arm. A stop 50 projects rearwardly from the bridge plate and constitutes a means for limiting the rocking movement of the crank. The shaft 57 extends forwardly through the mounting plate 15 and constitutes the indicator actuating shaft. This shaft is designed to extend through an opening 75 in the dial plate 10 which dial plate is provided with a scale 76 arranged in an arc with the opening 75 concentrically disposed relative thereto. The indicator or pointer 63 is fixed to the shaft 57 by means of a hub 64 and is arranged to move relative to the scale as is usual with devices of this character. A pulley 58 is fixed to the shaft 57 between the plates 15 and 54 and a spring 59 is wound about the pulley with one end secured thereto and the other end secured to the bridge plate 54 by passing the free end of the spring through a small aperture 77 in the end wall of the bridge plate. In the type of instrument illustrated in Figs. 1 and 2, the mechanism-containing casing 65 is of a size designed so that the mechanical unit hereinbefore described shall have a snug fit therein. One side of the casing, for convenience referred to as the bottom 30 side, is provided with a recess 66 opening from the front edge thereof to receive the hub 22 which extends therethrough. Opposite sides of the cylinder formed by the hubs 21 and 22 are provided with grooves 35 78 into which the edges forming the recess 66 have a sliding fit to fix the unit in place in the casing. If desired, the instrument may be supported by a back plate 68 which is shown attached to the casing by screws 40 passing therethrough into spaced bushings 67 formed in the back plate. This back plate is also provided with screw holes 69 constituting an additional means for fastening the instrument in any desired position. 45 In the modifications illustrated in Figs. 4 and 5, the casing is shown to be of a larger diameter designed to accommodate a larger dial plate having a scale of correspondingly larger diameter. With a scale of this type it is obvious that the indicator actuating shaft must be moved so that it will rotate about an axis concentrically disposed relative to the arc of the scale. For this purpose the mounting plate and bridge plate 50 are provided with a plurality of aligned small holes 70 constituting journal bearings for the indicator shaft. These bearings are concentrically disposed relative to the axis of rotation of the shaft 51 and 55 to the outside of the sector gear. Two of these bearings are illustrated in the drawings, but it is of course obvious that as many of these bearings may be provided as there are different size of dials to which the mechanical units are designed to coöperate.

The different casings are each provided with a glass retaining ring 71 for holding the front glass face 72 in position.

In operation, let it be assumed that a mechanical unit of the class described is carried in stock together with dials of different sizes and with the indicator shaft opening in the dials differently positioned relative to the recess 66 in the casing. When an order is received for a certain size speedometer, 70 the casing of that required size is assembled with one of the mechanical units. The indicator actuating shaft 57 is adjusted in the particular bearing 70 which will register with the opening in the dial plate when 75 the parts are assembled and the unit is inserted in the casing with its grooves 78 containing the edges of the casing at the recess 66. When the parts are assembled the set screw 53 is loosened and the crank 80 adjusted on the shaft 51 until the head 47 has a slight bearing engagement upon one of the disks 43. The sector gear 55 is adjusted on the shaft 51, if such an adjustment is necessary to preserve the meshing of the 85 same with the pinion 56. If necessary the device is calibrated to fit the particular dial used, which calibrating may be attained roughly by the adjustment of the spring 61 or a more refined calibrating may be attained by drawing more or less of the spring 59 through the opening in the bridge plate. The indicator is suitably adjusted on the shaft 57, the glass face is inserted in place and there is thus formed a complete article 90 of manufacture.

The instrument is mounted in position, as on a motor vehicle, with the shaft 20 suitably attached to the device, the speed of which is to be indicated. The rotation of 105 the shaft 20 will cause the weights 30 to move outwardly under the centrifugal force developed, which weights will act through the links causing the runner to approach the relative stationary stop. The initial portion 110 of this sliding movement of the runner, that is, the movement at low speed of the shaft, will be resisted by the relatively weak tension spring 41 and the continued movement of the runner will gradually bring into play 115 the resistance of the relatively heavy spring 40 thus progressively increasing the resistance to the movement of the runner with the increase in speed of the actuating element. This movement of the runner will continue 120 until such a speed is attained, such as will bring the stop 34 into engagement with the links limiting this reduction of angular relation and thus limiting the extent of movement of the runner and its weights. The lower 125 of the pair of disks 43 will bear on the head 47 of the crank to raise the same and rock the shaft 51, so that the unilateral movement of the runner will be transmitted into rotary movement of the shaft. This rocking of 130

the shaft 51 is transmitted through the gearing formed by the sector gear and pinion to correspondingly rock the indicator shaft 57 which in turn swings the pointer over the face of the dial plate 52 to indicate on the scale thereof the speed readings.

Should the speed of the shaft 20 decrease, the springs 40 and 41 in turn exert their tension to return the runner into its normal position shown in Fig. 2 and the spring 61 acts in co-operation with the spring 58 to return the indicator actuating mechanism into its normal inoperative position, thus swinging the pointer back into its zero position indicated in Fig. 6.

By means of a device of this character it is possible to fill orders for a variety of different size speedometers from a minimum number of composite parts carried in stock. 20 The expensive mechanical inserts may all be made of one standard size thus reducing the initial cost of construction and these different units may be made to fit the desired size casing, merely by shifting the position of 25 the indicator actuating shaft. This stock unit may be calibrated quickly and conveniently to fit any desired scale within the range of the instrument.

As all of the indicator actuating mechanisms are carried by the mounting plate, this plate and its attached parts may be readily removed as a unit thus providing ready access to the parts carried thereby. In this way springs of different tension may be substituted conveniently for the springs originally assembled therewith and cleaning and repairing of the several parts is facilitated. The indicator is held fixed in its speed controlled position on the dial and is not affected by the vibration of the support carrying 40 the instrument. This renders the instrument particularly adapted for accurate speed reading when used on a motor vehicle or on other vibrating machinery. The 45 adjustment of the end thrust bearing permits the mounting of the shaft in position fixed against longitudinal movement and the anti-friction means permits the easy rotation of the shaft. The bearing block 25 may 50 be adjusted from time to time to take up wear on the shaft without demounting the parts as access is provided to the same through the open end of the bore 24. All loose connection between the several parts is 55 eliminated as the spring 61 is of a tension sufficient to maintain the head 47 continuously in firm engagement with the runner 39 and the spring 59 maintains the teeth of the sector gear and pinion continuously in 60 bearing engagement with each other.

Ease of movement between the parts is attained further by reducing the friction between the runner and shaft. While the bearing of the crank upon one side of the 65 projecting flanges 43 has a tendency to cant

the runner on the shaft, this action is minimized by the centering of the spring engaging the upper end of the runner and by the spacing of the end bearings of the runner in their engagement with the shaft. Providing 70 the air-vents 45 between the ends of the runner bearing on the shaft permits air to escape from between the runner and shaft thus facilitating the sliding action of this member. The ease of operation of this device 75 is enhanced by the particular construction of the governor weights. The vibration of the casing has little, if any effect upon these weights as any vibratory movement to which the instrument may be subjected is taken up by the pivoted links 31 and 32 and any vibratory movement of the weights set up an oscillatory movement of the weights about their pivot pins 33, but this movement has little, if any effect, upon 80 the speed controlled member 39. It is obviously within the scope of this invention to fix the weight 30 to the link 32 and the drawings may be so read.

The spring 59 may be made as delicate as 90 desired, thus providing for a refined calibrating of the instrument by varying the tension of this spring. As the spring engages the last element of the indicator actuating mechanism, it positions this adjustment at the most vital point of the mechanism.

While I have shown and described, and have pointed out in the annexed claims, certain novel features of my invention, it will 100 be understood that various omissions, substitutions and changes in the form and details of the device illustrated and in its operation may be made by those skilled in the art without departing from the spirit of 105 the invention.

Having thus described my invention, I claim:

1. In a device of the class described, the combination with a dial, provided with a scale arranged in an arc, said dial having an opening therethrough concentrically disposed relative to said scale, of a mechanical unit adapted to be assembled with said dial to provide a complete instrument, said unit 110 including a support provided with a plurality of bearings, one of which is adapted to register with said opening when the dial is assembled with the unit, an indicator driving shaft extending through said registered bearing and opening and adapted to be mounted in any one of said bearings and speed controlled driving mechanism mounted in said unit and operatively connected to said shaft. 115

2. In a device of the class described, the combination with a casing and a dial having an opening therethrough, of a mechanical unit designed to be assembled with similar casings of different sizes and with the 120

- dial openings differently positioned, said unit including speed controlled mechanism comprising an indicator shaft shiftable relative to the unit to extend through the different 5 positioned openings in the different dials, driving mechanism mounted in the unit in relatively fixed position and a shiftable connection between said shiftable shaft and said driving mechanism.
- 10 3. In a device of the class described, the combination with a casing provided with means at one side for attaching the same to mechanical units of different sizes relative to the size of said casing, of a mechanical 15 unit of one of said different sizes adapted to be inserted into said casing and provided with means co-acting with said first named means for fastening the same in place in fixed relation thereto, said casing being provided 20 with an opening and said unit being provided with mechanical parts, one of which parts project through said openings and said part being adjustable in the unit to register with the opening in the casing.
- 25 4. In a device of the class described, the combination with a mechanical unit having a driving element and a driven element projecting therefrom and speed controlled mechanism operatively connecting said elements, one of said elements being shiftable 30 into different positions in said unit, a unit containing casing adapted to be assembled with said unit to form a complete instrument, said casing being provided with fixed 35 spaces adapted to accommodate said elements when the shiftable element is in that one of its different positions designed to be accommodated in the spaces thereof.
5. In a device of the class described, a 40 mechanical unit constituting a complete article of manufacture designed to be mounted in different characters of containing casings and comprising a support, a driving shaft mounted in said support, an indicator controlling shaft mounted in said support, speed controlled mechanism operatively 45 connecting said driving shaft with said indicator controlling shaft and means carried by the unit for fastening the same to any 50 one of the containing casings.
6. In a device of the class described, a mechanical unit complete in itself, and provided with means for mounting the same in a containing casing, said unit including a 55 support, a driving shaft mounted for rotary movement in said support, a member provided with an annular groove, slidably mounted on said shaft and operatively controlled by the speed thereof, a mounting 60 plate removably affixed to said support, an indicator actuating mechanism supported from said plate and removable as a unit therewith, said mechanism including a rounded head disposed in the annular 65 groove of said sliding member and remov-

able therefrom without disturbing either the mechanism carried by the shaft or the mechanism carried by the plate.

7. In a device of the class described, a mechanical unit complete in itself and comprising a circular frame provided with means for locating the same in an inclosing casing, a speed controlled member carried by said frame, a mounting plate removably affixed to said frame, an indicator actuating mechanism carried by said plate adapted to be operatively connected to said speed controlled member, parts of said mechanism being adjustable so as to be centrally disposed relative to said inclosing casing and 75 a dial having a scale curved about a center coinciding with the center of said inclosing casing.

8. In a device of the class described, a containing casing, a frame provided with 85 an end thrust bearing disposed within the casing, a boss having a threaded bore alined with said bearing and projecting exteriorly of the casing, a thrust bearing adjustably mounted in said threaded bore, a shaft extending through said adjustable thrust bearing and having an end mounted in said end thrust bearing, anti-friction devices disposed between said bearings and said shaft, said adjustable thrust bearing being provided 90 with means accessible through said boss from the outside of the casing for taking up wear on the parts and for regulating the longitudinal pressure between the shaft and said anti-friction means.

9. In a device of the class described, a skeleton frame designed to be mounted in an inclosing casing provided with an end thrust bearing, a boss having a threaded bore alined with said bearing, a thrust bearing adjustably mounted in said threaded bore, a shaft extending through said adjustable thrust bearing and having an end mounted in said end thrust bearing, anti-friction devices disposed between said bearings and said shaft, said adjustable thrust bearing being provided with means accessible through said boss for taking up wear on the parts and for regulating the longitudinal pressure between the shaft and said 100 anti-friction means and means for locking said shaft in position against longitudinal movement.

10. In a device of the class described, a circular frame provided with means for locating the same in a containing casing and provided with an end thrust bearing, a boss having a threaded bore alined with said bearing and designed to project through the containing casing, a thrust bearing adjustably mounted in said threaded bore, a shaft extending through said adjustable thrust bearing and having an end mounted in said end thrust bearing, anti-friction devices disposed between said bearings and said shaft, 115 120 125 130

said adjustable thrust bearing being provided with means accessible through said boss from the outside of the casing for taking up wear on the parts and for regulating the 5 longitudinal pressure between the shaft and said anti-friction means and a lock nut accessible from the outside of said boss for locking said shaft in position against longitudinal movement.

10 11. In a device of the class described, the combination of a shaft, a speed controlled sleeve slidably mounted on said shaft, said sleeve being provided with a vent hole to permit the escape of air from between the 15 sleeve and shaft.

12. In a device of the class described, the combination of a shaft, a sleeve slidably mounted on said shaft, the bore of said sleeve having longitudinally spaced reduced 20 portions engaging said shaft and providing an annular pocket therebetween, said sleeve being provided with an air vent leading from said pocket to the outside of the sleeve to permit the escape of air from said pocket 25 as the sleeve is moved along the shaft.

13. In a device of the class described, the combination of a driven shaft, a sleeve slidably mounted on said shaft and having a relatively long bearing thereon, means for 30 moving the sleeve along the shaft, means acting on said sleeve intermediate its length tending to twist the sleeve into binding engagement with the shaft, the bore of said sleeve being provided with a pocket intermediate its length thereby to reduce the 35 engaging surface of the sleeve with the shaft, said pocket being provided with means for permitting the escape of air from said pocket.

14. In a device of the class described, the 40 combination of a speed controlled member and an indicator actuating mechanism including a shaft, a crank mounted on said shaft, the free arm of said crank engaging said member to be rocked thereby, means 45 for adjusting said crank on said shaft whereby to insure an adjustable connection between said member and mechanism, a lever attached to said crank and resilient means acting on said lever to maintain a positive 50 bearing connection between the free arm of said crank and said member.

15. In a device of the class described, the combination with a speed controlled member, of an indicator actuating mechanism, 55 comprising a support, a pair of shafts mounted for rotary movement in said support, a crank and a segmental rack spaced apart and each fixed to one of said shafts, an indicator and a pinion fixed to the other 60 shaft, said rack meshing with said pinion and the free arm of said crank operatively connected to said speed controlled member.

16. In a device of the class described, the combination with a speed controlled member, of an indicator actuating mechanism,

comprising a support, a pair of shafts mounted for rotary movement in said support, a crank and a segmental rack spaced apart and each fixed to one of said shafts, an indicator and a pinion fixed to the other 70 shaft, said rack meshing with said pinion and the free arm of said crank operatively connected to said speed controlled member and resilient means engaging said crank to maintain the arm thereof in engagement 75 with said member.

17. In a device of the class described, the combination with a speed controlled member, of an indicator actuating mechanism, comprising a support, a pair of shafts 80 mounted for rotary movement in said support, a crank and a segmental rack fixed to one of said shafts and spaced from each other, an indicator and a pinion fixed to the other shaft, said rack meshing with said 85 pinion and the free arm of said crank operatively connected to said speed controlled member and resilient means acting on said pinion to maintain the teeth thereof continually in bearing engagement with the 90 teeth of the rack, said crank being adjustable independently of said resilient means.

18. In a device of the class described, the combination with a speed controlled member, of an indicator actuating mechanism, comprising a support, a pair of shafts mounted for rotary movement in said support, a crank and a segmental rack fixed to one of said shafts, an indicator and a pinion fixed to the other shaft, said rack meshing with said 95 pinion and the free arm of said crank operatively connected to said speed controlled member, resilient means acting on said pinion to maintain the teeth thereof continually in bearing engagement with the teeth of the 100 rack and means for adjusting the tension of said resilient means.

19. In a device of the class described, the combination with a speed controlled member, of an indicator actuating mechanism, comprising a support, a pair of shafts mounted for rotary movement in said support, a crank and a segmental rack fixed to one of said shafts, an indicator and a pinion fixed to the other shaft, said rack meshing with said 110 pinion and the free arm of said crank operatively connected to said speed controlled member and resilient means acting on said pinion to maintain the teeth thereof continually in bearing engagement with the teeth of the 115 rack, said resilient means acting on the pinion and rack in the opposite directions to maintain the teeth of the same in contact.

20. In a device of the class described, the combination with a speed controlled member, of an indicator actuating mechanism and a support therefor, said indicator mechanism including two shafts mounted for rotary movement in said support, one of said 125

- shafts operatively connected to said speed controlled member to be rotated by the movement of said member, said support having a plurality of bearings, each adapted to support the other shaft, said other shaft constituting a shiftable shaft adapted to move an indicator, and a driving connection between said shafts operable in all positions of said shiftable shafts.
21. In a device of the class described, the combination with a speed controlled member, of an indicator actuating mechanism and a support therefor, said indicator mechanism including two shafts mounted for rotary movement in said support, one of said shafts operatively connected to said speed controlled member to be rotated by the movement of said member, said support having a plurality of bearings, each adapted to support the other shaft, an indicator fixed to said other shaft, a scale for said indicator, and a driving connection between said shafts operable in all positions of said shiftable shafts.
22. In a device of the class described, the combination of a support which may be subjected to vibration or jerky movements, a driving shaft mounted for rotary movement in said support, a speed controlled member slidably mounted on said shaft, a centrifugally actuated member operated from said shaft and actuating said sliding member, and a loose connection between said centrifugally actuated member and said sliding member, said loose connection including a pivotal mounting for the centrifugally actuated member disposed to the inside of its center of mass, whereby vibratory movement of the support is taken up by said centrifugally actuated member.
23. In a device of the class described, the combination of a support which may be subjected to vibration or jerky movements, a driving shaft mounted for rotary movement in said support, a speed controlled member slidably mounted on said shaft, a centrifugally actuated member operated from said shaft and actuating said sliding member,
- and a loose connection between said centrifugally actuated member and said sliding member and a loose connection between said shaft and said sliding member whereby vibratory movement of the support is taken up by said centrifugally actuated member.
24. In a device of the class described, the combination of a support, which may be subjected to vibration or jerky movements, a driving shaft mounted for rotary movement in said support, a speed controlled member slidably mounted on said shaft, a centrifugally actuated member operated from said shaft and actuating said sliding member, a loose connection between said centrifugally actuated member and said sliding member and a loose connection between said shaft and said sliding member whereby vibratory movement of the support is taken up by said centrifugally actuated member, said connections having a common point of attachment with said centrifugally actuated member at its inner edge.
25. In a device of the class described, the combination with a speed controlled member, and an indicator actuating mechanism operatively connected therewith, a plurality of resilient means for resisting the movement of said speed controlled member, means for bringing the different resilient means into operative resisting engagement with the speed controlled member at different speed indicating positions of the indicator actuating mechanism and adjusting means operatively connected to said indicator actuating mechanism for calibrating the device whereby the device may be adjusted to fit any prescribed scale of speed readings when different types of said resilient means are substituted.

Signed at New Rochelle, in the county of Westchester and State of New York, this 13th day of May, A. D. 1915.

CLARENCE CARSON.
